UNITED STATES PATENT OFFICE.

WALLACE DURAND, OF NEWARK, NEW JERSEY.

UMBRELLA.

963,753.

Specification of Letters Patent. Patented July 12, 1910.

Application filed March 17, 1910. Serial No. 549,855.

To all whom it may concern:

Be it known that I, WALLACE DURAND, a citizen of the United States, residing at Newark, in the county of Essex and State of New Jersey, have invented certain new and useful Improvements in Umbrellas; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to a cup which is provided for holding the ends of umbrella ribs when the umbrella is shut, this cup being arranged on the end of the handle where it adjoins the rod, and the cup is designed to slide so as to release the ribs when the umbrella is to be opened, and it has a spring to normally force it to hold the ends of the ribs when the umbrella is shut.

Another object of the invention is to provide a cup of this kind which is formed so that when the umbrella is being shut, if the ribs are all grasped in the hand and the hand is squeezed, the ends of the ribs will force the cup longitudinally until the ribs are all within the rim of the cup, when the cup will snap back over the ribs and hold them in place.

The invention is illustrated in the accompanying drawing, in which—

Figure 1 is an elevation of the handle and the ends of the ribs of an umbrella showing the retainer holding the ends of the ribs in place. Fig. 2 is a section through the retainer showing the end of the handle and with the rod in elevation, and Fig. 3 is a section on line 3, 3, in Fig. 2.

The cup can be applied to any umbrella, the umbrella having the usual rod 10 on the end of which is fixed a handle 11, and the ribs 12, with the heads or ends 13 thereon, are of the usual construction. The retainer for the umbrella ribs is placed around the rod adjacent to the end of the handle and forms a finish for the juncture of the rod and the handle, in addition to its acting as a retainer for the balls on the ends of the ribs. The retainer comprises an inner casing 14 which is cylindrical and has an annular flange 15 on its end, the flange embracing the rod and also acting to limit the move-

ment of the cup, as will be described hereinafter.

Surrounding the inner casing, at a distance therefrom, is an outer casing 16 which rests on the flange 15, the inner and outer casings forming a chamber between them. In this chamber is arranged a coiled spring 17 which has one end abutting on a flange 18, although it will be evident that this flange is not essential, since the spring may 65 abut on the end of the handle 11. The other end of the spring is arranged to bear on a series of inwardly projecting lips 19, which lips project through the slots 20 in the outer casing and are thus permitted to move longitudinally, but are held against any rotation. The lips 19 are secured to or integral with the cup 20^a which holds the ends of the ribs and has a sleeve 21 thereon which surrounds the outer casing and slides thereon and also 75 on a shell 22 which is placed on the outer casing and extends partly over the handle to make a better finish. It will thus be seen that the spring normally presses the cup down so that the fingers 19 are normally 80 resting on the flange 15, and thus a limit of movement of the cup in this direction is established. The cup is provided with a downwardly turned rim which is annular and has its outer face 23 flat and inwardly 85 inclined so as to form a beveled face, which face acts to receive the balls or ends 13 of the ribs 12, and when the ribs are grasped in the hand and squeezed, the balls will bear against the face 23 and the cup will be 90 forced against the action of the spring until the ends of the ribs are against the rod 10, and then the cup will be snapped over them by the spring 17 and they are held tightly 95 in place until the cup 20^a is manually operated so that the ribs are all released. When the ribs are released by the movement of the cup they have enough tendency to spring out to enable them to clear the rod slightly, and when the cup is released and the balls 100 or ends 13 of the ribs are slightly away from the rod 10, the face 23 will act to engage them and then force them outward so as to clear the ribs away from the catch, which is operated when the umbrella is opened, and 105 thus make the opening of the umbrella more convenient.

Having thus described my invention, what I claim is:—

1. A retainer for umbrella ribs compris-

110

ing an inner casing, an outer casing, a spring between them, the outer casing being slotted, a cup, and fingers on the cup projecting through the slots and bearing on one end of the spring, the cup having an annular inturned flange, the inturned flange having an outer flat face to receive the ends of the umbrella ribs.

2. A retainer for the ends of umbrella ribs comprising an inner casing having a flange on the end, an outer casing resting on the flange, the outer casing having longitudinally arranged slots therein, a cup having inwardly projecting fingers projecting through the slots in the outer casing and resting on the flange of the inner casing, a

spring having one end abutting on the inwardly turned fingers of the cup, a sleeve on the cup surrounding the outer casing, the cup having a downwardly projecting and inwardly turned annular rim to receive the ends of the umbrella ribs whereby pressure on the ribs will cause the cup to be forced against the action of the spring.

In testimony, that I claim the foregoing, I have hereunto set my hand this 11th day of March 1910.

WALLACE DURAND.
